DEVICE FOR ARRESTING UNDULATIONS
IN BRIDGING STRUCTURES.

Merle R. Wolfard, Cambridge, Mass.

Application November 5, 1945, Serial No. 626,661.

7 Claims. (Cl. 14—1)

1

This invention relates to devices for arresting undulations in a bridging structure.

More particularly, the invention relates to improvements in bridging structures in which there is a principal lengthwise load-sustaining element having inflections such that the advent of live loading tends to cause undulation of that element.

It is an object of the invention to provide bridging structures, that are of light weight, in which the desired stability is attained with little or no addition of weight beyond what is required for the loads that are to be carried.

The bridging structures concerned may be bridges of the suspension type, or bridges of the truss type, or may be trusses of other sorts and for other services in which winds, or traffic, or machinery, or other disturbances, tend to cause vibrations. The usual materials for such structures are highly resilient, e. g., steel. In the case of steel, the elasticity of steel is such that practically all of the work done in deflecting a steel element is present as energy to move that deflected element back to its initial position, and the momentum imparted by this return movement carries the element beyond its initial position. If there are repetitive impulses, in harmonic sequence, each impulse adds an increment to the amplitude of the undulations.

It is a specific object of the invention to arrest the initial movement which each deflecting impulse tends to produce. For many practical purposes it is sufficient to arrest only those undulations which the smaller deflecting impulses tend to produce, and to permit deflection under the impact of large live loads. This is permissible because the undulations by the heavier loads are greater in length, and are slower in sequence. For example, it has been well established that suspension bridges, which are entirely adequate for resisting disturbance by heavy traffic, may nevertheless become greatly disturbed, or even destroyed, by relatively light repetitive impulses of higher frequency caused by winds.

The prompt and positive arresting of the undulating movements that the smaller forces tend to produce is sufficient to prevent the building up of those large high frequency amplitudes of movement which are objectionable and may become destructive. This positive arresting means also restricts travel of the shorter, higher frequency undulations along the span.

The invention arrests incipient movements by providing a dead load burden that is sustained in common by two particular regions of a principal load-carrying element. Such a common

2

burden is available to be transferred to and be sustained by either of said regions, that is, to "migrate" to one or the other of said regions, as live loading tends to cause rise, first, at the one and then at the other, of those regions. One of these particular regions is located in each end-half of the span. The said common burden may be a normal part of the structure, or may be something added for the purpose. In so far as it becomes released by either of these two regions, where it is sustained in common, it will migrate to the other of those regions—i. e., will be transferred to and become sustained at that other.

15 The invention is applicable in bridging structures of various types. Among the included types are those in which a principal element hangs with sag, and sustains its loads by tension, as, the cable of a suspension bridge. And, trusses are included, in which a principal load-sustaining element which sustains its load by compression is inclined upward from ends which are fast to the lower chord of the truss, the middle portion of this element being approximately horizontal.

20 Preferably the inclination of these end portions is less than 45° from the horizontal.

The accompanying drawings show embodiments of the invention, diagrammatically. In them:

25 Figure 1 is a side elevation illustrating a simple bridge construction, showing only a main load-sustaining element and migratory loading means coacting therewith;

Figure 2 is an end elevation of the main load-sustaining element of Figure 1, in cross section at 2—2, enlarged;

30 Figure 3 is a side elevation of apparatus for illustrating the principle of migration of loading, as it may be applied to the arresting of vertical movements;

Figure 4 is a side elevation of a truss which has two panel-loaded points connected for migration of loading;

35 Figures 5, 6 and 7 are greatly enlarged details of parts of Figure 4, in which Figure 5 is an end elevation in section on the line 5—5; Figure 6, a side elevation of the region of inflection of the principal load-carrying element; and Figure 7 is a side elevation at the connection of the compression element to the tension element, in medial section;

40 Figure 8 is a side elevation of a six panel truss, having three panel-loaded points connected for migration of loading;

45 Figure 9 is a side elevation of a ten panel truss,

in which there are three panel-loaded points for migration of loading, and the inclined parts of the principal load-sustaining element are supported by struts at their mid-portions;

Figure 10 is a side elevation of a truss having two panel-loaded points connected for migration of loading, like Figure 4, with an extension of two panels at each end;

Figure 11 is a side elevation of a truss having three panel-loaded points connected for migration of loading as in Figure 8, to which an extension of two panels is added at each end; and

Figure 12 is a side elevation of a truss having a mid-portion arrangement similar to that of Figure 11, but having its end extension panels of conventional type.

In the accompanying drawings, Figure 3 represents illustrative balance beam apparatus in which the arresting of vertical movement is accomplished by migration of loading. The element 30 is a horizontal support on which two struts 31 stand as an inverted V supporting a pivot 32 at the mid-point of the beam 34, this pivot 32 corresponding to the knife-edge of a balance. Equidistant, at opposite ends of the beam, are the pivots of clevises 35, 36 through which tension elements 37, 38 pass for loading the ends of the beam. Each tension element has its outer end fast to the horizontal support 30, beyond the end of the beam 34; has its middle portion passing through the clevis 35 or 36; and has its inner end beneath the pivot 32, fast to the free inner end of a radius bar 40 whose pivot 41 is at a horizontal distance on the support 30—so that these inner ends of the tension elements 37, 38 can move up or down, but cannot move lengthwise of the horizontal support. A weight 42 hangs on that free end of the bar, and so constitutes a dead load which is a burden that is common to these two tension elements and is imposed by them on their several clevises 35, 36.

Thus, each limb of each tension element 37, 38 applies to its respective clevis 35, 36 a loading whose vertical downward component equals half of the weight 42; the total downward vertical loading at the clevis 35 is equal to the weight 42; the total vertical downward loading at the clevis 36 is equal to the same; and the beam 34 is balanced. Inasmuch as the loadings at clevises 35 and 36 are produced by a burden which they sustain in common, any part of that common burden which one of these clevises ceases to sustain becomes imposed on the other clevis.

These being in balance, the adding at 35, of a loading such as would start a down swing of the point 35, initiates a relaxing of the tension member 37, and causes the loading at 36 to increase. But if the load added at 35 does not exceed double the weight 42 the beam will not move appreciably, because the migration, i. e., the shifting, of some or all of the burden of the weight 42 from 35 to 36 will maintain a state of balance.

This migration of loading may be understood by considering a numerical example. Assuming that the weight 42 is one pound, so that there is initially one pound of dead load at each clevis, and that the apparatus is in a state of balance, and assuming further that an added load of one pound becomes incident at 35, simulating the advent of a live loading on an end portion of a bridge, then one-half pound of dead loading migrates from 35 to 36, and produces a fresh balance of loading, viz., one and one-half pounds at each point 36 and 35. The fact that the dead load 42 is sustained in common at 35 and 36

promptly and positively arrests that rise of the end 36 of the beam, and that fall of the end 35 of the beam, which the weight added at 35 otherwise would cause.

5 The total dead load that is carried by both at 35 and 36 is available to migrate to either 35 or 36. That is, the total dead loading that was originally carried at both regions 35, 36, can be imposed at either of them.

10 For another example, assume as before that the weight 42 is one pound, and that the apparatus is in balance, and that an added weight of two pounds becomes incident at 35. Then a new balance is reached as the whole of the initial loading of one pound that was at 35 migrates to 36, making the beam 34 be in balance with two pounds of loading at each end 35, 36.

If this two pounds of live load added at 35 should become transferred to the other end 36

20 of the beam, as when a traffic load moves across a bridge, then the total of dead load which is available for migration, two pounds, migrates back from 36 to 35 and arrests movement of the beam at the incipience of its fall at 36 and of 25 its rise at 35. This persistence of the beam in balance continues so long as no magnitude of a loading added at 35 or at 36 exceeds the capacity of the apparatus, which, under the assumed conditions of the numerical example, reaches its limit 30 with an added loading of two pounds at either end of the beam. If either end suffers incidence of more than two pounds added loading there will be movement of the beam.

Figure 1 illustrates how the invention may be applied in a bridge of simple construction, as, for crossing a ravine, in which the migratory loading means can be located under a mid-portion of the span. The principal load sustaining element 10 has each of its ends 12 held at a fixed level and held against lengthwise movement. It is subject to migratory loading at each of two regions, 18 and 28, which are at approximately equal distances from the center of the span, at which regions there are pulleys over which the 40 loading cables 14, 24 pass from their anchorages 13, 23, beneath their respective end portions of the bridge, to a lever 26 whose fulcrum 22 is secured at a convenient place beneath the bridge. The lever is powered by a weight 20, and has its work arm in two branches 15, 25 which respectively are connected to the cables 14, 24 for loading in common two particular regions of the principal load sustaining element 10, by transfer through the 45 pulley connections 19 from the pulleys 18, 28. Tautness of these cables 14, 24 can be adjusted by any suitable means, as turnbuckles 21.

The imposing of burden at the regions indicated in each end-half-portion of the span, when the structure is static, applies at each such region 50 a magnitude of dead load burden which exceeds that dead load burden which is imposed at any other region of equal extent in the same end-half-portion of the principal sustaining element.

The cables 14, 24 being equal in stress, when 55 the structure is static, an advent of live loading on the element 10 at a region 18 or 28 will produce migration of loading between these regions 18, 28. This migration is of dead load burden imposed on those regions in common by the lever 26 and cables 14, 24 in the manner explained above for migration between the points 35, 36 of Figure 3.

Most favorable results are obtained when the two regions 18, 28 of Figure 1, are located at about equal distances from the center of the span,

and are about four-tenths of the length of the span apart. However, benefits are had if they are located anywhere within the range of two-tenths to six-tenths of the length of the span apart.

Figure 1 exemplifies how the invention may be applied to a load-sustaining element of a bridging structure which hangs with sag between supports. The element 10 sustains load by tension, as the cables do in a suspension bridge of customary type. This element, and the cables, tend to rise in one end-half-portion when a traffic load comes upon the other end-half-portion of the span. The invention is likewise effective in dealing with aero-dynamic disturbances, in which wind impulses may tend to lift one region of the bridge more than another.

Figure 2 shows the principal load sustaining element 10 having a cross section in the form of an inverted T, in which the vertical stem of the T contributes stiffness to the structure. This is an advantageous distribution of material because, the main loading is sustained by tension between the end supports, at least in the mid-portion of the span, and this tension is in the lower flange of the T.

In the application of migratory loading illustrated in Figures 1 and 3 the common dead load burden is added to the structure which is to be stabilized. However the common load burden for migratory loading may be provided by a part of the structure which is being stabilized, as, for example, by parts of the platform and its appurtenances.

The structures of Figures 4, 8 and 9, have some features of ordinary trusses, have the general appearance of ordinary trusses, and are herein called "trusses," but they differ from the usual truss in that the structure is arranged to provide dead load burden sustained in part at each of two particular regions of a principal load sustaining element, so that the major portion of that sustained load is available to migrate to either of said particular regions upon the advent of live loadings which tend to cause rise first at one of said regions and then at the other of those regions. There is a top horizontal portion of the truss from whose ends strut portions incline downward and outward to the tension chord below, where they are held against lengthwise slip relative to that tension chord. These horizontal and inclined portions sustain a compression load, and should be considered as a continuous compression element extending between its end connections to the tension chord below it. This compression element is herein designated the principal load sustaining element of the truss. In each end-half-portion of the span it has an inflection at a point where there is a tendency to rise when a load is applied at the similar point in the other end-half-portion; and these points are the particular regions at which a burden of dead load is sustained in common, for migration of dead load to either region to prevent its rise, so to stabilize the span.

Figure 4 shows an application of migration of loading in simple form, in a truss having five panels in which the middle two of the four intermediate panel-loaded points are connected for migration of loading. The load which is available to migrate is those parts of the platform and its appurtenances which are hung at those panel-loaded points.

The principal load-sustaining compression element 50 rises, at an inclination, from the tension

chord 52 at one end of the span to an inflection point 55, whence it extends approximately horizontally to the other inflection point 56, and thence it inclines downward to the tension chord 52 at the other end of the span. The distance of the points 55, 56 from each other is preferably within the range of two-tenths to six-tenths of the length of the span. The span is considered to extend between the points where the compression element 50 is secured to the tension element 52. This element 50, which may be a channel bar with the channel downward, has each of its ends held against lengthwise slip relative to the tension chord 52. This holding may be accomplished in any convenient manner, an illustrative method being shown in Figure 7 wherein a saddle piece 51 secured to the lower chord 52 has a notch 53, into which the web of the channel fits, to sustain endwise thrust and vertical load. The channel bar is shown as having its flanges cut away at its points of inflection 55, 56, as indicated in Figure 6 at 54, and the web is bent to form the inflection. In a channel bar thus arranged and loaded, the compression load applied to the web between the flanges tends to bend the bar downward between those loaded points. The weight of the bar also tends to bend the bar downward. These two tendencies are sufficient to assure that the middle of this element will never be deflected to above the horizontal by any vibrating tendency. The making of this nonprismatic section thus contributes to stability. Figure 5 shows how a tie, as 72, may be conveniently pivoted between the flanges of a channel bar element 50. The element 50 is not necessarily one continuous piece; it may be of joined pieces, and these may be connected at the points of inflection by pivots or otherwise. This element 50 functions as a single element, it is conveniently here so treated. In Figure 4 the dead load of a bridge platform is represented as being separate weights 58 hung from panel-loaded points 60, 64, 68 and 70. The panel-loaded point 60 has ties 61, 62 respectively connecting it to the inflection points 55, 56. The panel-loaded point 70 is connected by ties 71, 72 respectively to the same two inflection points 56, 55. By this arrangement the dead loads which are at the panel-loaded points 60 and 70 are sustained in common at the inflection points 55, 56. Therefore these loads constitute a common burden which is available to migrate to whichever point 55, 56 tends to rise upon advent of live loading.

A tie 65 connects the inflection region 55 to the panel-loaded point 64 which is under the adjacent inclined part of the compression element; and similarly tie 69 connects the other inflection region 56 to the panel-loaded point 68 under the other end incline. Preferably the inclined end portions of the element 50 are set at an angle less than 45° from the horizontal, and in consequence the vertical component of any rotative movement about the held end of the element 50 exceeds the horizontal component of the same movement which is lengthwise of the span. This minimizes longitudinal movement of the upper part of the truss; and the vertical arresting action of the migration of loading is so positive in cases of ordinary traffic that all movements which may be caused by that are inconsequential. In cases of extraordinary overloading, as when a military tank passes over a highway bridge, the invention permits the loading to deflect the element 50, without damage.

Figure 8 is similar to Figure 4 in the general

arrangement of the compression element 80 and lower chord 82, which correspond to 50 and 52 in Figure 4; the inflection points 85, 86, which correspond to 55, 56; and the ties 95, 99, which correspond to the ties 65, 69, and run to the panel-loaded points 94, 98. It differs in that there are three panel-loaded points 100, 105, 110 connected for migration of their loading to the two inflection points 85, 86 respectively by ties 101, 102; 106, 107; and 111, 112. It differs also in that the compression element 80, between its inflection points 85, 86 is set with a slight bend which keeps its mid-portion below the horizontal level of those points; and that a strut 87 extends downward from the element 80 at that bend to the panel-loaded point 105. This is in contrast to the usual practice of elevating the center of a truss. That tends to instability, but in this construction any tendency of the mid-portion of the element to move is in the direction in which the migratory loading ties 106, 107 will restrain its movement. The straight dotted index line 89 indicates horizontality. The set of the element 80 below this line is exaggerated for clearness.

In Figure 9 the tension chord is 122, and the compression element is 120. This structure has ten panel-loaded points of which three, 130, 135 and 140, are connected for migration of loading to its points of inflection 125, 126. The other panels may be supported in any suitable way, that which is illustrated being by ties from the inflection point. From the mid-portion of each inclined part of the compression element 120 there is a strut 127 approximately normal thereto and extending to a panel-loaded point in the lower chord; and there is an inclined tie to the lower chord between this strut and the end of the chord.

Figures 10, 11 and 12 show arrangements by which the structures in Figures 4 and 8 can be utilized in trusses having a greater number of panels. In such cases the supporting means, at the ends of the "span" in which the stabilizing structure of the invention is embodied, may each be at a distance from the pier that supports its end of the full span of the bridge. That is, the supporting means of the "span" which embodies the invention are at the points where the compression element 50 or 80 is held against lengthwise slip in the respective tension chord 152 or 182 of the truss.

In Figure 10 a nine panel truss embodies the structure of Figure 4 in its mid-portion. The horizontal portion of the compression element 50 has extensions 151 at each end, beyond which are inclined extensions 153. From the junction of the horizontal and inclined parts of these extensions, at each end of the truss, ties incline downward to panel-loaded points, in the tension chord, one of these reaching the panel-loading point at which the element 50 terminates. This provides a truss in which there are eight panel-loaded points, only two of which are connected for migration of loading.

In Figure 11 a ten panel truss embodies in its mid-portion the structure of Figure 8. The horizontal portion of the compression element has extensions 181 at each end, beyond which are inclined extensions 183. From the junction of the horizontal and inclined parts of the extensions of the compression element, at each end of the truss, ties incline downward to panel-loaded points in the tension chord, one of these reaching the panel-loaded point at which the element 80 terminates.

Figure 12 embodies the structure of Figure 8 in

its mid-portion and shows how extensions at each end can be made by adding panels of usual truss type, two of such panels being shown so added.

In Figures 10, 11 and 12, having this greater number of panels, the common dead load burden that is available to migrate is a smaller proportion of the total dead load of the platform than is available in the trusses of Figures 4 and 8. Nevertheless the dead load burden imposed on the points of inflection of members 50 or 80 exceeds the dead load burden which is imposed at any other region of equal extent along said members of the truss, in the same end-half-portion of the span; and the stabilization thus provided will be satisfactory for many purposes.

In the structures thus described, the manner of stabilization, and its quality, prevent the building up of excessive movements, and so provide a structure in which little strength of the principal load sustaining elements need be provided much beyond that which is required merely to sustain the live loads.

By reason of the prompt arresting of undulations at their incipience, and by reason of the greater flexibility of the structure under extreme loading, the maximum stresses which any given live loading imposes on the main load sustaining elements are greatly reduced, as compared with usual bridging structures. Therefore a lower factor of safety may be used, permitting a bridge to be safe when made with less weight and less cost of material. The greatly reduced possibility of longitudinal movement of the upper part of a truss structure permits the making of that upper part lighter; and the fact that it is lighter makes its holding more secure, so that another decrement of weight becomes possible.

It is intended that the appended claims shall have expressions suitable for the patent to cover whatever of patentable invention is herein disclosed relative to stabilizing of bridging structures by loading, in common, regions in opposite end portions of the span for migration of dead loading from one end-half-portion of the span of the structure to the other to arrest rise in that other.

This is a continuation in part of my copending application Serial No. 435,686, now Patent No. 2,413,019 issued December 24, 1946, which is now limited to bridging structures which are stabilized by migration of loading upward and downward between regions that are in the same end-half-portion of the span.

I claim as my invention:

1. A structure having migratory loading means for arresting its own undulations—being a bridging structure, extending between supporting means and sustaining dead load and live load along the span between those supporting means, of a type in which there is a principal lengthwise element which is inflected so that an incipient depressing of that element in one end-half-portion of the span below its static position tends to cause rise of that element in the other end-half-portion of the span, and so that the said principal element extends from a said supporting means at an angle of less than 45° with the horizontal—said arresting means comprising a distribution of dead load relative to two particular regions of the said principal lengthwise element, each of which regions sustains a magnitude of dead load burden which exceeds that imposed on any other portion of equal extent along that element in the same end-half-portion of the span when the structure is static;

each end-half-portion of the span having one of these particular regions, they being spaced apart a distance which is in the range of two-tenths to six-tenths of the length of the span between said supporting means; there being tying means extending from a common dead load burden directly to each of said regions, this common burden being sustained in part at each said region when the structure is static, and said part constituting a portion of the said greater magnitude of dead load burden at a said region; at least a major portion of the said common burden, so sustained in common, being available to migrate through the tying means to either of said regions, upon the advent of live loadings which tend to cause rise first at one of said regions and then at the other of these said regions.

2. A structure having migratory loading means for arresting its own undulations as in claim 1, in which the said principal lengthwise load-carrying element is one that hangs with sag between said supporting means, has anchorage connections at its ends; and in the span sustains loading by tension pull on said connections.

3. A structure having migratory loading means for arresting its own undulations, as in claim 1, being a truss in which the said principal lengthwise element is a compression element having an approximately horizontal middle portion between points of inflection from which its end portions incline downward to the tension chord of the truss at a said supporting means and are there held against lengthwise slip relative to that tension chord; the said particular regions being at these points of inflection in said compression element.

4. A structure having migratory loading means for arresting its own undulations, as in claim 3; further characterized in that said tying means include, for each said region, a plurality of ties pitching inward and downward from that region to points which severally sustain panel dead load; a plurality of panel-loaded points being each thus tied to both of said regions to impose on those regions in common the load which is sustained at the plurality of said panel-loaded points.

5. A structure having migratory loading means for arresting its own undulations, as in claim 3; further characterized in that said tying means include, for each said region, a plurality of ties pitching inward and downward from that region to points which severally sustain panel dead load; a plurality of panel-loaded points being each thus tied to both of said regions to impose on those regions in common the load which is

sustained at the plurality of said panel-loaded points; the said approximately horizontal portion of the compression element having its mid-portion set at a level slightly below the straight line between its points of inflection; and there being a strut extending downward from that mid-portion to a said panel-loaded point at the tension chord.

6. A structure having migratory loading means for arresting its own undulations, as in claim 3; further characterized in that said tying means include, for each said region, a plurality of ties pitching inward and downward from that region to points which severally sustain panel dead load; a plurality of panel-loaded points being each thus tied to both of said regions to impose on those regions in common the load which is sustained at the plurality of said panel-loaded points; there being also at each said region a tie pitching outward and downward to a panel-loaded point beneath the respective inclined said end-portion.

7. A structure having migratory loading means for arresting its own undulations, as in claim 3; further characterized in that said tying means include, for each said region, a plurality of ties pitching inward and downward from that region to points which severally sustain panel dead load; a plurality of panel-loaded points being each thus tied to both of said regions to impose on those regions in common the load which is sustained at the plurality of said panel-loaded points; there being also at each said region a tie pitching outward and downward to a panel-loaded point beneath the respective inclined end portion; a strut rising from the last mentioned panel-loaded point to a mid-portion of the said inclined end portion; and a tie from the joinder of this strut and end portion, pitching downward and outward to another panel-loaded point.
